UNITED STATES PATENT OFFICE.

CHARLES JAMES, OF NEW YORK, N. Y.

AUTOMATIC SPEED-REGULATING DEVICE FOR RAILROADS.

1,049,280.

Specification of Letters Patent. Patented Dec. 31, 1912.

Application filed February 24, 1912. Serial No. 679,601.

To all whom it may concern:

Be it known that I, CHARLES JAMES, a citizen of the United States, and a resident of the borough of Manhattan, city, county, and State of New York, have invented certain new and useful Improvements in Automatic Speed-Regulating Devices for Railroads, of which the following is a specification.

10 My invention relates to devices for automatically regulating or limiting the speed of railway trains or like vehicles.

Railway regulations for the reduction of speed at certain points or places, such as 15 junctions, switches, crossings, curves, etc., where high speed would involve danger to the train are difficult of enforcement and, when such regulations are disobeyed accident frequently results.

20 By the use of my invention I produce a mechanical device of simple, durable and inexpensive construction which will be positive in operation, will be composed of few parts, will be unaffected by weather conditions, and substantially indestructible.

25 My improved device is adapted to be actuated by the force of impact of a train moving at or above a predetermined rate of speed, to stop or signal a train in any known manner such as by causing the air brakes to be applied, cutting off the power or if desired causing a visible or audible signal to be given or closing a switch.

30 My invention may be readily connected with a switch so that the opening of the switch will set the device in position to be actuated by a train attempting to take the switch at or above a predetermined rate of speed, and may be so arranged as to close 35 the switch upon the actuation of the contact lever.

The preferred embodiment of my invention consists of a train stop, comprising a rock shaft of any desired length, extending 40 parallel and located contiguous to the railroad tracks, pivoted in suitable standards and having an arm at one end adapted to be 45 swung into the path of the train to engage any suitable known device for applying the 50 brakes or cutting off the power, or giving a signal, and said arm is actuated into operative position by means of a weighted arm at the opposite end of the rock shaft; a trigger device, comprising an angular lever pivoted 55 intermediate its ends in suitable bearings or standards, engages the weighted arm to

hold the weight suspended and thus prevent the parallel extending shaft from rocking to move the train engaging arm into operative position, and an actuating device comprising a rock shaft pivoted in suitable bearings and provided with a plurality of arms, one of which extends into the path of the train so as to be struck by a suitable projection carried thereby, another arm for engaging and releasing the trigger device to operate the train engaging arm thereof into operative position when a blow of given force is struck upon the same or in other words when a train moving at a speed at or above a predetermined speed strikes such actuating arm, and another arm weighted in any suitable manner to retard the pivotal movement of the actuating arm and means for shifting the weight relatively to said arm to vary the retarding action or effect thereof.

In the accompanying drawings in which similar reference characters designate corresponding parts throughout the several views, Figure 1 is a side elevation of a device embodying my invention. Fig. 2 is an end view of the device shown in Fig. 1; Fig. 3 is a plan view of the device shown in Fig. 1; Fig. 4 is a side elevation of a modified form of device embodying my invention; and Fig. 5 is a side elevation of another modified form.

Referring now to Figs. 1, 2 and 3 of these drawings, A designates what I shall term a "train stop", comprising a rock shaft a journaled in bearings a' a'' on standards A A' and provided at one end with an arm a^2 , extending at substantially right angles thereto and provided at its other end with an arm a^3 extending at a right angle in the opposite direction and in substantially the same plane as the arm a^2 . The arm a^3 is provided with a weight a^4 . Obviously if the weighted arm is permitted to fall by gravity the arm at the opposite end of the rock shaft a^2 will be rocked into vertical or operative position and into the path of a train. In order to retain this arm in its normal, horizontal, or inoperative position I preferably employ a trigger device comprising as illustrated an angular lever B pivoted intermediate its ends in a bearing b on a standard B' . As shown the angular lever B is prevented from rotating in one direction by means of a stop b' secured upon the standard or bearings B' in any

suitable manner. One end of such lever engages the arm a^3 of the train stop device and retains the same in horizontal position and out of the path of the train. The end or toe of the lever engaging such arm is prevented from moving downwardly by means of the stop device b' but as will be obvious if the other end of the lever B is depressed the toe at the opposite end will 10 partially lift the weighted arm and ride by the same, thus permitting the weighted arm to drop and causing the arm a^2 to move into the path of the train.

My preferred form of device for releasing the trigger to permit the train stop device to be swung into operative position is shown in Figs. 1, 2 and 3 and will now be described. In said figures a shaft C is pivoted in suitable bearings $c\ c$ and is provided 20 with a plurality of arms C' C^2 and C^3 fixed thereon extending radially therefrom. The shaft and arms are permitted to rotate in one direction only being prevented from rotating in the opposite direction by means of 25 a stop c' on the standard C^4 . As shown, the arm C' is secured to the shaft C and extends without an inclosing casing D and projects into the path of a projection E , carried by the train or other vehicle F . When the arm 30 C' is struck obviously the shaft will be rotated, carrying the arms C^2 C^3 therewith. The arm C^2 extends into the path of the trigger B and when the arm C' is struck a blow of a given force the arm C^2 will engage the trigger B to actuate the train stop. The arm C^3 extends as shown in the opposite direction from the arm C^2 and is provided with a weight c^4 threaded on a screw 35 thread c^5 on the arm C^3 , thus providing 40 means to shift the weight toward or away from the pivot to vary the retarding effect of such weight on the pivotal movement of the shaft C .

The operation of the device thus described is as follows: The actuating device is set in such relation to the trigger that when a blow of predetermined force or velocity is administered to the lever C' it will 45 rotate a given distance, engage and release the trigger to permit the train stop to swing into operative position. Of course a train going at a given velocity will always administer a given blow to a lever set in a given position and consequently my actuating lever may be so proportioned and positioned 50 relatively to the trigger that a train moving at or above a predetermined rate of speed and striking the lever at such speed will cause the trigger to release the train stop 55 and swing the same into operative position in advance of the train.

In Fig. 4 I have shown a modified form of device embodying my invention. In said figure, the train stop is in all respects similar to that above described in relation to

Figs. 1, 2 and 3 and such description need not here be repeated. In this figure an angular lever G , having arms G' G^2 is pivoted at g upon a suitable standard H and the arms G' G^2 as shown are arranged at an angle of over 45° and are pivoted at the meeting point thereof. The arm G' extends into the path of the train and the arm G^2 is provided with a weight g^2 slidingly mounted thereon. A trigger device J comprising 70 an angular lever having arms pivoted intermediate its ends and arms j' j^2 are pivoted on a standard J' and one end of such lever J engages the weighted arm a^3 of the train stop device and holds such arm in horizontal or suspended position and retains the actuating arm a^2 out of its operative position. When the arm G' is struck by a train it will rotate upon the pivot g and will cause the weighted arm G^2 to be swung upwardly 75 and the weight g^2 will be swung outwardly on said arm G^2 by centrifugal force. The levers G^2 and J are so positioned that when the weight g^2 slides outwardly from centrifugal force a sufficient distance, it will 80 strike the trigger arm j and cause the weighted arm a^3 to be released, thus rocking the shaft to move the arm a^2 into operative 85 position to stop the train.

In Fig. 5 I have shown another actuating 90 device comprising the guiding sleeve L inclined in relation to the plane of the track. Within the guiding sleeve L I arrange a slide M provided with a projecting arm m extending into the path of the train through 95 a slot d^5 in the inclosing casing D^5 . To the end of the slide M I attach in any suitable manner a cord N which extends rearwardly over a pulley P and a weight W is secured to the other end of such cord. At a suitable 100 distance from the slide M I pivot a trigger device Q having one arm q extending into the path of the slide and its other arm q' supporting the weighted arm a^3 in a manner similar to that above described. 110 When a train moving at or above a predetermined rate of speed strikes the projecting arm m a blow sufficient to move the trigger q out of engagement with the arm a^3 it will permit said arm to swing into operative 115 position to stop or signal the train.

Having described my invention, I claim:

1. A track device for the purpose specified, embodying a member adapted to swing into operative position, means for retaining the same in inoperative position and means in the path of the train and operable by a blow of predetermined velocity delivered by the train for releasing said swinging member.

2. In combination with a track train stop comprising a rock shaft of suitable length extending parallel to the track and having an arm at its forward end extending at substantially a right angle thereto, means 120

- at the rear end of said shaft for automatically rocking said shaft to move said arm into operative train engaging position, a device for normally retaining said arm in 5 inoperative position and means in the path of the train and operable by a blow therefrom of predetermined velocity for releasing said arm to swing into operative position in advance of the train.
- 10 3. The combination with a rock shaft suitably pivoted and extending parallel to the railroad track, an arm at one end of said rock shaft for engaging speed-controlling mechanism on the train; and means at the 15 other end thereof for automatically rocking said arm into upright operative position; a trigger device retaining said arm in

inoperative position, a pivoted actuating-device located contiguous to the track, having an arm extending into the path of the 20 train and another arm for engaging and releasing the aforesaid trigger device when the first arm is struck a blow of predetermined velocity by the train, and means for varying the extent of oscillation of said releasing arm. 25

In witness whereof, I have hereunto set my hand to the foregoing specification in the presence of two subscribing witnesses.

CHARLES JAMES.
